UNITED STATES PATENT OFFICE.

JAMES H. FOOTE, OF CINCINNATI, OHIO.

THILL-COUPING.

SPECIFICATION forming part of Letters Patent No. 277,416, dated May 8, 1883.

Application filed November 27, 1882. (No model.)

To all whom it may concern:

Be it known that I, JAMES H. FOOTE, a citizen of the United States, residing at Cincinnati, Ohio, have invented new and useful Improvements in Thill-Couplings, of which the following is a specification.

My invention relates to the pivotal fastenings, usually termed "thill-couplings," employed to secure the shafts of road-vehicles to the axle, and is intended to provide a cheap and efficient fastening in which all lost motion due to wear can be taken up from time to time as may be necessary, and rattling be thereby prevented.

To this end my invention consists in the employment of a partially-expansile bolt formed in two parts by longitudinal division, with serrated or otherwise inclined adjacent surfaces normally registering with and fitting against each other, so as to constitute exteriorly a cylindrical bolt, but expansile by withdrawing one portion of the bolt upon the other or others longitudinally.

I have shown a preferred form of my invention in the accompanying drawings, in which Figure 1 represents a front view of an ordinary thill-coupling, showing the jaws in axial section, the bolt in position, but with the thill-iron removed. Fig. 2 is a side view of the coupling. Fig. 3 is a side view of the bolt removed and with its parts a little separated. Fig. 4 is an end view of the same.

Referring to the drawings in aid of the description, in which the parts are designated by letters of reference, A designates the ordinary buggy-clip thill-coupling; a a', the jaws between which the thill-iron is inserted, and B the pivotal bolt embraced by the thill-iron.

The principle of my invention consists in dividing the bolt B longitudinally into two parts and forming the adjacent surfaces into inclined planes with relation to each other, so that upon drawing one of the parts into which the bolt is divided longitudinally upon the other or others the bolt is enlarged radially. It is obvious that the adjacent surfaces may be formed in a variety of ways, either as a single continuous incline or a number of them. In practice I find it desirable to divide the surfaces into three or more inclines each, and as a matter of convenience and economy in construction the surfaces may be simply serrated, as shown

in Figs. 1 and 3, in which the bolt is shown divided into the parts b b', constructed in detail as follows: The principal portion b of the bolt B is divided for only a portion of its length, as shown, and is otherwise cylindrical and screw-threaded at one end. The smaller portion, b', is fitted to that first described, and at its end is formed a head, b². The two portions placed together form a cylindrical bolt, fitting snugly the perforations through the jaws a a, and projecting slightly at both ends beyond the jaws. The head b² thus rests against the outside of the jaw on one side, and prevents the movement of the portion b' inward, while the threaded end of the part b projects through the opposite jaw and receives a nut, which, in turning, acts against the outside of the jaw and withdraws the part b independently in its direction. This independent movement of one part of the bolt upon the other, as will be obvious, causes them to spread apart and occupy more space radially in a plane perpendicular to their general plane of division, which is the object sought to be attained, and as the part b' projects through one of the jaws a and partly through the other, part of the expansion occurs within the perforations of the jaws. At such portions of the general length of the bolt the two members b b' stand somewhat apart, so that as a net result of the movement the expansion is greatest at the central section of the bolt between the jaws, being prevented from enlargement at the jaws by the embracing-ring of metal. This is permitted by the bending of the metal of the part b', and at the same time sets the bolt B firmly in the jaws, thus preventing any rotation of the bolt, and consequently preventing any wear at those points. It will also be obvious that the action of the nut against the outside of one of the jaws and the resistance of the head b² against the outside of the opposite jaw, both acting toward the common center, tend to compress the jaws together and take up any lost motion of the thill-iron sidewise. A shallow depression in the jaw, in which the head b² fits when in position, may be provided as a means of preventing rotation of the bolt independently of its expansion.

My invention may be applied to many other situations than thill-couplings, and indeed in any mechanism requiring an expansile pivot.

I claim as my invention and desire to secure by Letters Patent—

1. In a thill-coupling, a cylindrical pivot-bolt formed by longitudinal division into two parts having correspondingly-inclined adjacent surfaces, one of such parts provided with an end stop and the other with a screw-nut, by which one part may be moved longitudinally upon the other in the coupling-jaws, and the bolt be thereby radially enlarged, substantially as set forth.
2. In combination with the jaws $a a'$ and the

thill-iron of a shaft-fastening, the bolt B, composed of members $b b'$, constructed as described, and a fastening-nut, arranged and operating as set forth. 15

In testimony whereof I have hereunto set my hand in the presence of two subscribing witnesses.

J. H. FOOTE.
